E. BROUGHAM

YOKE RING LOCK AND REIN GUARD

Filed June 26, 1922

INVENTOR
EDWARD BROUGHAM.

BY *Johnston & Langford*
ATTN.

UNITED STATES PATENT OFFICE.

EDWARD BROUGHAM, OF PENNANT, SASKATCHEWAN, CANADA, ASSIGNOR OF ONE-HALF TO JAMES P. BAKER, OF HENRIBOURG, SASKATCHEWAN, CANADA.

YOKE-RING LOCK AND REIN GUARD.

Application filed June 26, 1922. Serial No. 570,961.

To all whom it may concern:

Be it known that I, EDWARD BROUGHAM, a resident of Pennant, in the Province of Saskatchewan and Dominion of Canada, have invented certain new and useful Improvements in Yoke-Ring Locks and Rein Guards, of which the following is a specification.

This invention relates to improvements 10 in yoke ring locks and rein guards; and has for its objects to provide a means whereby the reins will be prevented from getting caught or tangled in the forward end of a tongue of a vehicle; to provide 15 a means whereby the rein guard will also act as a ring lock; to provide a resilient member designed to be located at the forward end of a vehicle pole, the end of which is protected by means of a channel 20 member carried by the pole.

Further objects are to provide a means whereby the ring lock and rein guard is removable.

Still further objects are to provide an improved yoke ring lock and rein guard that is simple in construction, not liable to go out of repair, and generally to adapt the several parts to better perform the functions required of them.

30 And it consists essentially of the improved construction and arrangement of parts hereinafter described in detail in the accompanying specification and drawings.

In the drawings:

35 Figure 1 is a perspective view of the forward end of the vehicle pole, equipped with the improved device.

Figure 2 is a side elevation of the same.

40 Figure 3 is a side view of the same, showing the improved device in section.

Figure 4 is a cross-section on the line 4—4, Figure 3.

Figure 5 is a side elevation, showing in detail the improved rein guard.

45 Figure 6 is a perspective view of the channel member.

Figure 7 is a perspective view of an alternative form of rein guard, and ring lock.

In the drawings, like characters of reference indicate corresponding parts in all the figures.

Referring to the drawings:

A represents a vehicle pole of usual construction, the forward end of which is 55 formed on the underside with a recess 10

designed to engage a channel member 11. The cross limb of the channel member is designed to be so engaged by the recess 10 that it will be flush with the underside of the pole A, and the flanges 12 and 13 thereof will extend downwardly, as shown in Figures 2 and 4.

The usual iron works B are provided comprising in this case, a metallic member 14 designed to be slid over the forward end 65 of the pole A in between the two flanges 12 and 13 of the channel member 11. A portion of the metallic member 14 engaging the underside of the pole A is formed adjacent to its end with a bend 15 provided 70 with registering orifices.

A resilient member 16 is provided which is bent in wedge formation and has one of its bent ends 17 extending between the flanges 12 and 13 of the channel member 75 11. The remote end of the resilient member 16 is formed with a threaded stem 18 designed to extend through the orifice of the bend 15 and engaged by a nut 19 bearing against the bend 15, in order to securely retain the resilient member 16 in position adjacent to the bend 15 and in engagement with the flanges 12 and 13 of the channel member 11.

When a team of horses is being harnessed 85 to a vehicle, the pole of which is equipped with this improved device, the yoke ring is forced between the metallic member 14 and the resilient member 16, the latter being forced downwardly in order that its extension 17 may be disengaged from the flanges 12 and 13 of the channel member 11, and thus allow a space in which the ring can be slid.

As soon as the ring has reached the free 95 space between the resilient member 16 and the bend 15, the resilient member will spring upwardly in normal position and its extension 17 will bear against the underpart of the metallic member 14 between the flanges 100 12 and 13, and thus lock the ring in position on the pole.

The resilient member 16 being of wedge shape will prevent the reins from being caught and tangled on the forward end of 105 the pole, which very often happens with the usual ring lock of the ordinary vehicle poles.

As soon as the rein comes in engagement with the resilient member 16, it will slide upwardly following the inclined wall of the re- 110

slient member 16, and thus be led over the forward end of the pole A.

When the rein guard and ring lock is to be made of flat steel, it is formed in the shape 5 shown in Figure 7, when it comprises a triangular member 20 having an upright portion 21 bored as at 22 in order to engage the shank of a suitable bolt designed to secure the member 20 to the bend 15 of the 10 iron works B.

As many changes could be made in the above construction, and many apparently widely different embodiments of my invention within the scope of the claims, constructed without departing from the spirit 15 or scope thereof, it is intended that all matter in the accompanying specification and drawings shall be interpreted as illustrative and not in a limiting sense.

20. What I claim as my invention is:

1. A yoke ring lock and rein guard comprising, in combination, a wagon tongue formed with a recess on the underside, an inverted channel member adapted to fit into 25 said recess, a tip for the tongue adapted to

engage with said channel member and formed with a double bend adjacent thereto, a wedge member of resilient material bent at one end to fit between the channel member and said tip and adapted at the other end to 30 extend through said double bend and means for securing the wedge in said double bend.

2. In a device of the character described, the combination with a vehicle tongue having a tip thereon designed to engage with a 35 channel member in the underside of said tongue, of a double bend on the tip, a wedge of resilient material adapted at one end to engage the channel member and at the other end to engage the double bend, a yoke ring 40 on the tongue between the wedge member and said bend and whereby the wedge member forms a rein guard for the tongue.

In witness whereof I have hereunto set my hand in the presence of two witnesses.

EDWARD BROUGHAN.
